Primary Examiner—Lucy Lieberman*(74) Attorney, Agent, or Firm*—Lars S. Johnson(57) **CLAIM**

The ornamental design for a bottle portion, as shown and described.

DESCRIPTION

FIG. 1 is a perspective view of a bottle portion embodying a new design;

FIG. 2 is a front elevational view of the bottle portion depicted in FIG. 1, the side and rear elevational views being identical;

FIG. 3 is a top plan view of the bottle portion depicted in FIG. 2; and,

FIG. 4 is a bottom plan view of the bottle portion depicted in FIG. 2.

The broken line environmental showing is for illustrative purposes only and does not form part of the claimed design.
